UNITED STATES PATENT OFFICE

2,460,340

FEEDING MECHANISM

Hubert E. Dickerman, Springfield, Mass.

Application January 19, 1946, Serial No. 642,178

2 Claims. (Cl. 271—2.5)

1

This invention relates to improvements in feed mechanism and is directed more particularly to a feeding mechanism adapted among other uses for feeding successive portions of metal stock such as wire, ribbon, rods, bands and the like into a machine or apparatus which acts on the stock.

In connection with such a machine as a punch press or the like, which has relatively movable members carrying cooperating metal working devices, the said members move towards and away from one another for such operations on the stock as punching, cutting, forming, drawing, and numerous other operations. Such machines use successive parts or portions of bars, rods, tubes, strips, wires and the like to perform successive operations and produce successive objects or pieces of work.

The apparatus of this invention is adapted for use in connection with such machines and the cooperating metal working devices thereof to feed thereto successive portions of the metal to be worked on. The mechanism is adapted to intermittently feed or to feed in a step by step manner such material as wire, metal strip, rods, bars, tubes in various forms, sections and sizes in timed relation with a machine or apparatus working or acting on successive portions or lengths of material.

According to one embodiment of the invention the mechanism thereof may be associated with a die set which, as is well known, includes a set of relatively movable cooperating die members adapted to be associated with the relatively movable members of various machines such as a punch press, so that the die members are moved towards and away from one another for performing various operations.

The feeding mechanism of this invention, by being associated with the die set, may be removed from the machine therewith so that various die sets may have feeding mechanisms more or less permanently associated therewith. This eliminates the necessity of adjusting the common form of feed mechanism to a particular die set when it is associated with the machine, thereby eliminating the loss of time, expense and other objections incident to such a procedure. Otherwise, of course, the same feed mechanism of the invention may be applied to numerous and various different die sets if it should be so desired or to machines of various types.

According to U. S. Patent No. 2,188,473 of January 30, 1940, the feed mechanism is operated by a cam which is associated with the upper member

2

of a die set. The upper member of such a die set is secured to the movable member of a press or the like and the lower member of a die set is secured to the stationary member of said press.

5 The movable member of the press has a definite distance of movement relative to the stationary member so that since the feed mechanism is operated by the cam the length of stock which may be fed is limited by the length of stroke of the press. This is objectionable for the reason it is frequently desired to feed longer lengths of stock than the length of stroke of the press will provide.

10 According to this invention, a die feed is provided which is characterized by means which will feed longer lengths of stock relative to the stroke of the press than is possible with the feed mechanism of the patent referred to. This is accomplished by a novel combination and arrangement of parts hereinafter to be described.

15 With the foregoing and various other novel features and advantages and other objects of my invention as will become more apparent as the description proceeds, the invention consists in 25 certain novel features of construction and in the combination and arrangement of parts as will be hereinafter more particularly pointed out in the claims hereunto annexed and more fully described and referred to in connection with the 30 accompanying drawings wherein:

Fig. 1 is a plan view of feeding mechanism embodying the novel features of the invention;

Fig. 2 is a side elevational view of the feeding mechanism shown in Fig. 1;

35 Fig. 3 is a longitudinal sectional view through the feeding mechanism shown in Figs. 1 and 2;

Fig. 4 is a cross sectional view through one of the rolls of the apparatus illustrating means for preventing rotation of the roll in one direction; and

40 Fig. 5 is a sectional elevational view on the line 4—4 of Fig. 2.

Referring now to the drawings more in detail, the invention will be fully described.

45 Upper and lower members of a die-set are represented by 2 and 4. These will have cooperating die members secured thereto and they are carried by an upper movable part of a press and the lower stationary part thereof. The upper part of the press moves up and down relative to the lower part so that the die members coact for operating on a length of material which is fed therebetween by the mechanism to be described.

50 A cam 6 is fixed to the upper member 2 and

has sloping faces 8 and dwell faces 10. As the upper member moves downwardly the faces 8 of the cam engage and operate the feed mechanism for feeding a length of stock to the dies. The dwell faces 10 arrest operation of the feeding mechanism while the upper member moves for the coaction of the die members on the length of stock which has been fed between the dies.

A base 12 is provided for securing to the lower member of a die set or to the stationary member of a press and spaced guides 14 extend upwardly therefrom. As the upper member 2 moves downwardly the rear side of the cam 6 slides along the guides as in the patent referred to.

Side rails 16 extend outwardly from the base portion 12. Inner members 18 inside the rails have outer plates 28 and 21 outside said rails secured thereto by screws 22 or the like. The plates are arranged to slidably embrace the rails for back and forth movements. The base and side rails provide a support for carriages as will appear.

Lower shafts 24 have opposite ends secured against rotation in the inner members 18. Blocks 26 are slideable up and down in guideways 28 provided in the inner members 18 and opposite ends of upper shafts 30 are fixed against rotation in said blocks.

Lower rolls 32 are rotatable on the lower shafts 24 in the direction of the arrows only and upper rolls 34 are rotatable on the upper shafts 30 only in the direction of the arrows. This may be accomplished in various ways but as an example, the shaft 30 as shown in Fig. 4 is provided with slots 36 in which pawls 38 are disposed for locking the rolls to the shaft to prevent counter-clockwise rotation of the rolls relative to the shaft. Springs 40 may be provided for urging the pawls into locking position.

Caps 46 have opposite ends secured to the inner members 18 and have bars 46 movable up and down therein. Screws 48 in opposite ends of the bars act on springs 50 which bear on the blocks 26. The upper rolls may move upwardly against the action of the springs and thereby the rolls yieldingly engage a strip of stock. Levers 52 are pivoted in the caps and have projections 53 for engaging the bars 46. By this means, the bars may be released to remove the pressure of the springs from the blocks 26, that is when the levers 52 are swung upwardly the bars 46 are released.

The inner and outer members 18, 20 and 21 and the caps 46 constitute inner and outer carriages 60 and 62 each of which has a pair of coacting rolls rotatable relative thereto.

The members 21 have cam rolls 64 rotatable thereon which are engageable by the cam 6. Rods 66 fixed to bosses 68 of the members 21 are slideable through ears 70 extending from rails 16 and compression springs 72 around the rods 66 are disposed between the bosses and ears. These springs urge the inner carriage 60 inwardly when released by the cam. Nuts 76 adjustable on the outer ends of rods 66 are adapted to abut the ears 70 and limit movement of the inner carriage 60 as it moves inwardly.

A transverse member 78 is secured to the inner members 18 of the outer carriage 62 and a link 80 has one end pivoted thereto at 82. A lever 84 is pivoted at 86 to a transverse member 88 which is associated with the rails 16 and has one end pivoted at 90 to link 80. A link 92

pivoted at one end 94 to the inner carriage 60 has its opposite end pivoted at 96 to lever 84.

The connections described provide simultaneous movements of the carriages.

5 As the upper member 2 moves upwardly from the position shown in Fig. 2, the springs 72 move the inner carriage 60 inwardly. In this movement of the carriage 60 and because the rolls thereof cannot rotate in a direction opposite 10 to the arrows, they grip and feed inwardly the stock between them.

Simultaneously with this inward movement of the carriage 60 the outer carriage 62 through the link and lever connections is moved outwardly. The rolls thereof since they may rotate in the direction of the arrows allows the stock to be drawn therethrough by the rolls of carriage 60.

When the carriages are in their spaced apart relation the inner carriage will have fed a length 20 of stock inwardly, the length being equal to the length of travel of said carriage and the outer carriage will be in an outer position to grip and feed a length of stock inwardly.

As the upper member 2 descends and the cam 6 engages the rolls 64, the inner carriage 60 is moved outwardly or rearwardly and the outer carriage 62 is moved inwardly. As the outer carriage moves inwardly because the rolls 32 and 34 thereof cannot rotate in a direction opposite 30 to the arrows said rolls grip and feed a length of stock inwardly while the rolls of the inner carriage allow the passage of stock therebetween.

Thus, while the carriages are moving from the relatively adjacent positions shown to a separated position, the inner carriage is feeding stock inwardly while when the carriages are moving from separated positions to adjacent positions the outer carriage is feeding stock inwardly. This makes it possible to feed a greater 40 length of stock than has been possible heretofore.

Means is provided for separating the rolls as they arrive at their adjacent position. Separation of the rolls frees the stock for the action 45 of the dies which is desired. This is accomplished by separators 89 which have inner ends pivoted on the upper shaft 30 of the inner carriage 60. Extensions 92 of the separators pass beneath the upper shafts 30 of the outer carriage and have inclined faces 94 engageable by said shafts 30.

Studs 86 carried by inner members 18 underlie the separators and adjusting screws 88 threaded in the separators are adapted to bear 55 on said studs. By the adjusting screws 88 the separators may be raised or lowered. As the carriages approach their adjacent inner positions the shafts 30 of the upper rolls of the carriage 62 engage the inclines 94 of the separators 60 which through the action of the screws 88 on the studs causes the upper rolls of the carriages to be elevated against the action of the springs thereby to release the stock.

The transverse member 88 may be provided 65 with a slot 90 as shown for securing thereto guide means for guiding stock into the feed mechanism.

The invention may be embodied in other specific forms without departing from the essential 70 characteristics thereof. Hence, the present embodiments are therefore to be considered in all respects merely as being illustrative and not as being restrictive, the scope of the invention being indicated by the appended claims rather than 75 by the foregoing description, and all modifica-

tions and variations as fall within the meaning and purview and range of equivalency of the appended claims are therefore intended to be embraced therein.

What it is desired to claim and secure by Letters Patent of the United States is:

1. Unitary strip feeding mechanism adapted for operation by the cam of a movable member of a die set comprising in combination, a base having longitudinal and transversely spaced side rails extending outwardly therefrom, an inner carriage and an outer carriage extending between and slideable in opposite directions on said rails, said inner carriage disposed adjacent said base and said outer carriage disposed outwardly of said inner carriage, spring means urging said inner carriage inwardly towards said base, said inner carriage provided with cam engaging means whereby it is moved outwardly against the action of said spring means by said cam, a transverse member fixed to outer ends of said side rails, a lever pivoted intermediate its ends to said member, a link having opposite ends pivoted to said outer carriage and to one end of said lever and a link having opposite ends pivoted to the inner carriage and an opposite end of said lever arranged whereby as the inner carriage moves towards and away from said base said outer carriage is moved away from and towards said inner carriage and base, spring pressed upper and lower shafts in each said carriage, coacting strip engaging rolls on said shafts, and clutch means between each of said rolls and the shaft therefor permitting rotation of said rolls in one direction only and arranged whereby as the carriages are moved towards said base the rolls are held against rotation to grip a strip for feeding it inwardly.

2. Unitary strip feeding mechanism adapted for operation by the cam of a movable member of a die set comprising in combination, a base having longitudinal and transversely spaced side rails extending outwardly therefrom, an inner carriage and an outer carriage extending be-

tween and slideable in opposite directions on said rails, said inner carriage disposed adjacent said base and said outer carriage disposed outwardly of said inner carriage, spring means urging said inner carriage inwardly towards said base, said inner carriage provided with cam engaging means whereby it is moved outwardly against the action of said spring means by said cam, a transverse member fixed to outer ends of said side rails, a lever pivoted intermediate its ends to said member, a link having opposite ends pivoted to said outer carriage and to one end of said lever and a link having opposite ends pivoted to the inner carriage and an opposite end of said lever arranged whereby as the inner carriage moves towards and away from said base said outer carriage is moved away from and towards said inner carriage and base, spring pressed upper and lower shafts in each said carriage, coacting strip engaging rolls on said shafts, and clutch means between each of said rolls and the shaft therefor permitting rotation of said rolls in one direction only and arranged whereby as the carriages are moved towards said base the rolls are held against rotation to grip a strip for feeding it inwardly and separator members carried by the inner carriage engageable by the upper shaft of the outer carriage to move said shaft upwardly and separate the rolls of the outer carriage when said carriages are adjacent one another.
